UNITED STATES PATENT OFFICE.

CARL J. HOLMGREN AND ERIK J. YOUNGQUIST, OF MINNEAPOLIS,
MINNESOTA.

DESIGN FOR A HAT-PIN.

SPECIFICATION forming part of Design No. 27,735, dated October 19, 1897.

Application filed January 9, 1897. Serial No. 618,654. Term of patent 14 years.

To all whom it may concern:

Be it known that we, CARL J. HOLMGREN and ERIK J. YOUNGQUIST, citizens of the United States, residing at Minneapolis, in the county of Hennepin and State of Minnesota, have invented and produced a certain new and original Design for Hat-pins; and we do declare the following to be a full, clear, and exact description of the invention, such as will enable others skilled in the art to which it appertains to make and use the same.

Our invention has relation to a new and original design for a hat-pin; and it consists of a pin of the configuration and ornamentation shown in the accompanying drawing, in which we have represented the pin in a plan view.

1 is the body of the pin, reversely curved

at 2, and formed with a tapering part 3, and provided with an ornamental head 4. 20

The leading feature of our design comprises the pin and its circular disk-shaped head 4, scalloped on its periphery, and having arms extending from a central setting to form kite-shaped spaces that are provided 25 with settings of contrasting colors.

What we claim is—

The design for a hat-pin, as herein shown and described.

In testimony whereof we hereunto affix our 30 signatures in presence of two witnesses.

CARL J. HOLMGREN.

ERIK J. YOUNGQUIST.
